WINDOW ADJUSTER

John W. Cramp and George W. Dooley,
San Bernardino, Calif.

Application April 9, 1937, Serial No. 135,926

4 Claims. (Cl. 292—265)

As the title of this invention would indicate, the device of this invention relates to means to adjust windows, that is, to adjust the degree of window opening and to provide means to keep the window in adjusted position.

There are a number of devices now on the market, which are designed to accomplish the broad objects of the device of this invention, however, in all of the contemporary adjusters of which applicants have knowledge, complicity, fragility and cost are objectionable characteristics, which taken together with awkwardness of operation, forbid their satisfactory use, and it is with this thought in mind that we have conceived the device of the present invention and have reduced it to commercial form.

Therefore, with the foregoing as a premise, it may be stated that the object of the present invention is to provide a window adjuster which is simple in construction, easy to operate, rugged and reliable, and of low cost.

Other objects, features and advantages may appear from the accompanying drawings, the specification and the subjoined claims.

In the drawings, of which there are two sheets:

Figure 1 is an elevational view of the exterior of a window of the type adapted to be applied with the device of this invention.

Figure 2 is a sectional elevation taken on line 2—2, Figure 3, showing the device of this invention after installation, and showing the adjuster in position to swing the window outwardly.

Figure 3 is an elevational view showing the inner side of a window to which the device of this invention has been applied.

Figure 4 is a view in elevation of one of the elements used to accomplish the purposes of this invention.

Figure 5 is a plan view of the device shown in Figure 4.

Figure 6 is a plan view of another of the elements used in the device of this invention.

Figure 7 is a view in elevation of the device shown in Figure 6.

Figure 8 is a view in elevation of the adjuster bar used in the device of this invention.

Figure 9 is a sectional view in plan, drawn to a larger scale than the figure upon which it is based, the figure is taken along line 9—9, Figure 2.

Figure 10 is a view in elevation, showing the adjuster bar in operative position.

Figure 11 is a plan view in section showing the adjuster bar in operative position.

Figure 12 is a view partially in section, as taken

on line 12—12, Figure 11, showing the device of this invention in installed position.

Figure 13 is plan view of the adjustable bar of this invention.

The device of this invention, as indicated by the reference character 20 is adapted to co-operate with a swingable window 22, to effect opening or closing thereof through various degrees of adjustment.

The window 22 is mounted upon hinges 24 in a frame 26, in the usual manner, and as is usually the case with this type of window, a screen 28 is placed across the inner face of the window in the manner shown in Figure 2.

The adjuster bar of this device comprises a 15 length of flat, flexible steel 30, provided with groups "A" and "B" of teeth or notches 68 in the lower edge thereof, while a finger grip or handle 32 is provided upon one end of the bar. Openings 34, through which screws 36 may be inserted, are formed in the opposite end portion of the bar 30.

That portion of the bar which is secured to the rail 38 by means of screws 36, is adapted to lay flat thereagainst, while at a point indicated by the reference character 44, the bar is bent outwardly at approximately 60 degrees, as shown in the drawings. The remainder of the bar is straight, its end, as above stated being provided with a finger grip or handle 32, not only as a matter of convenience, but also as a matter of finish.

A slot 46 formed in either the lower rail of the screen 28, or in a member 48, of similar dimension, is adapted to permit the bar 30 to move back and forth therethrough. A face plate 50 is well adapted to cover the slot formed in the member 48, and also serves to guide the bar as it moves back and forth in following the window 22. The slot or guide 52 is enlarged at 54 to provide clearance for the teeth or notches 68 as the bar 30 bends in moving through its path of travel. The face plate is secured to the window sill 56 by means of screws 58, while a keeper 60 having a base member 61, a vertical leg 62, and an overhanging lip 64, is adapted to hold the bar 30, and to prevent its protruding into a room, where it might otherwise interfere with curtains, blinds, etc.

The lower interior edge of the enlargement 54 is positioned above the base 66 of the face plate to provide a latch 75 which is slightly higher than the depth of the teeth 68, in order that the bar 30 may be able to use the full depth of the teeth to effect a locked connection, and also to pre-

vent the bar from scraping or otherwise marring the finish of the base 66.

Details of window construction do not enter into the concept of the device of this invention, except insofar as swingable windows in their broader conception, are necessary as a functional element of the invention.

All windows employ jambs 10 and in windows of the swingable type, it is frequently found that 10 the jamb varies in width. It is therefore necessary that means be provided to compensate for variations in width of jamb, and it is for this reason that we have provided a group "A", of closely set teeth in the bar 30.

15 It will be apparent that by closely spacing the teeth, we are able to provide practical means to accommodate windows having jambs of varied width. Outwardly from tooth group "A", the notches are spaced to provide varying degrees 20 of window opening adjustment, as indicated by notch grouping "B", see Figure 8.

It will be noted that the bar 30 is provided with a slight bend 40, which extends across the width thereof, (see Figure 8) the purpose of which is 25 as follows. In securing the bar 30 to a window, that part of the bar indicated by the reference character 41 is laid parallel with the rail 38 of the window, and is of course held in position by screws 36, thereby projecting the handle portion 30 32 in a downward direction because of the bend 40 which directs the handle portion at a tangent to that portion of the bar which is secured to the rail 38 of the window. The purpose of this construction is to firmly mesh the teeth 35 or notches with the latch 75, and to remove the necessity for hand placement of the bar, or the teeth thereon, in engagement with the latch, for as constructed, the bar will automatically engage the latch 75, unless prevented from doing 40 so, by upward pressure on the handle portion thereof.

To use the device of this invention, it is only necessary to follow the procedure to be now described. Assuming the window to be in closed 45 position as shown in Figures 9 and 11, it is only necessary to remove the bar from under the lip of the keeper 60, whereupon the bar swings to the approximate position shown in Figure 2. The bar is now lifted to free the teeth or notches 68 from 50 engagement with the latch 75, and is then thrust outwardly, thereby causing the window to also swing outwardly.

After the desired amount of window opening is obtained, the bar 30 is released, thereby causing 55 the notch or tooth 68 most nearly to the proper degree of opening to rest astride the latch 75 of the face plate 50, thereby securing the window in open, locked position.

The total number of teeth or notches 68, and 60 the exact gradations thereof on the bar 30 may be varied to meet the general average of weather conditions in any given part or section of the country, or to meet the individual requirements of the property owner, without departing from 65 the spirit of the invention.

From the foregoing description it will be apparent that we have provided a cheap, reliable, rugged, simple and highly efficient window adjuster.

70 It is obvious that various changes and modifications and variations may be made in prac-

ticing the invention in departure from the particular showing of the drawings and description, as given, without, however, departing from the true spirit of the invention as defined by the scope of the appended claims.

We claim:

1. The combination in a swingable window, of means to adjustably vary the position of said window, said means comprising a strip of flat flexible metal, said strip of flat flexible metal being deformed whereby its top edge does not conform with a horizontal line, means to operatively secure said strip to said window, said strip of flat flexible metal being provided with variably positioned notches, a guide through which said strip may move, means in said guide to engage said notches whereby said strip may be held in locked position, said deformity in said strip being adapted to constantly urge said strip into engagement with said locking means. 15

2. An adjuster for swingable windows, said adjuster comprising a strip of relatively thin, flat flexible metal, said metal being deformed and having a portion bent at an angle to the remaining portion, one of said portions being adapted to be secured flatly to a rail of said window, the other of said portions being adapted to extend outwardly and downwardly at an angle from said rail, notches in the lower edge of said strip of metal, a fixed guide for said strip of metal 30 through which it is adapted to move and with which said notches are adapted to cooperate to support said adjuster in fixed horizontal position. 25

3. An adjuster for swingable windows, said adjuster comprising a strip of flat, thin, flexible metal, said strip being formed with a deformity dividing said strip into opposing end portions tangential to one another, one of said tangential portions being adapted to be secured flatly to a 40 window rail and in horizontal relation therewith, the other of said tangential portions extending from said window rail, a fixed guide for said metal strip, notches on one edge of the said metal strip, said guide being provided with an edge 45 portion adapted to be nested in a selected notch whereby said metal strip and the window associated therewith are held in fixed position. 35

4. An adjuster for swingable windows, said adjuster comprising a strip of flat, thin, flexible metal, said strip of metal being formed with a plural number of deformities, one of said deformities dividing said strip into end portions tangential to one another, one of said end portions being secured flatly to a window rail and 50 in horizontal relation therewith, the other of said deformities breaking the top edge of said metal strip from a true horizontal line whereby the other of said tangential portions extends downwardly as well as inwardly from said window rail, said inward direction resulting from the one end portion being tangential with said flatly secured end portion, notches on one edge of said metal strip, a fixed guide for said metal strip, said guide being formed with an edge portion 55 adapted to be nested in a selected notch whereby said metal strip and the window associated therewith are held in fixed position. 60
